Chas. S. Gilley *R. B. Langford*

United States Patent Office.

ROBERT R. CAMPBELL, OF LOWELL, MASSACHUSETTS, ASSIGNOR TO
LOWELL MANUFACTURING COMPANY, OF SAME PLACE.

Design No. 4,873, dated May 9, 1871.

DESIGN FOR A CARPET-PATTERN.

The Schedule referred to in these Letters Patent and making part of the same.

'o all whom it may concern:

Be it known that I, ROBERT R. CAMPBELL, of the
ity of Lowell, county of Middlesex and State of Mas-
achusetts, have invented and produced a new and
riginal Design for a Pattern to be Inwrought into
'wo or Three-ply, Ingrain, and other Carpeting in such
olors as may be desired; and I do hereby declare that
he photographic prints accompanying this specifica-
tion do give and convey, to any one skilled in the art
f carpet-weaving, a more definite and thorough de-
cription of the nature of my invention than it is in
he power of language otherwise to convey, and are
sufficient to enable any one skilled in the art of car-
et-weaving to use my invention.

Claim.

What I claim as my invention, and desire to secu-
by Letters Patent, is--

The configuration of the design hereunto annexed
when made by being inwrought into two or three-ply
ingrain, or other carpeting in the form similar to the
photographic prints accompanying this specification.

R. R. CAMPBELL.
